UNITED STATES PATENT OFFICE.

JOHN LOVEJOY, OF WEST LEBANON, NEW HAMPSHIRE.

SWITCH-ROD AND COUPLER.

SPECIFICATION forming part of Letters Patent No. 269,530, dated December 26, 1882.

Application filed October 12, 1882. (No model.)

To all whom it may concern:

Be it known that I, JOHN LOVEJOY, a citizen of the United States, residing at West Lebanon, in the county of Grafton and State 5 of New Hampshire, have invented certain new and useful Improvements in Switch-Rods and Couplers; and I do hereby declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 The object of my invention is to provide a switch-rod and coupler, which shall be cheap, simple, strong, and effective, which can be easily attached and detached without disturbing the rest, which will at all times preserve the 20 gage by allowing the slack resulting from constant jarring to be taken up easily. To this end I combine with the rails a switch-rod and sliding collars of peculiar construction, fully set forth in the following description.

25 In the accompanying drawings, Figure 1 is a side view of one end of my device with rail attached. Fig. 2 is a vertical longitudinal section of the other end. Fig. 3 is a plan view.

Similar letters refer to similar parts.

30 B represents the switch rod or bar. It is made of iron or steel. Near the ends of said rod are grooves b b. These grooves are so made as to form solid clutches a a for the outer flanges of the rail. The inner walls, w, of the 35 grooves are vertical. They do not impinge upon the inner flange of the rail, but are some distance to the rear of it, to allow the insertion of the rail and wedge-key, the latter fastening the sliding collars in one groove. This construction gives simplicity, and does not weaken the rod as much as a second slot passing through it in the rear of the collar would.

40 C are sliding collars for the purpose of fastening and securely holding the rails in the 45 grooves. These collars are recessed across their faces to form lips c c. The upper ones close tightly upon the inner flange of the rail. Both the upper and under lips are alike, so that when one is disabled the lower one can 50 be used in its place by revolving the collar upon the rod. Hence it will not be necessary to throw away the collar because one lip is out of order. Back of these lips the collars

are made in the form of a solid bridge, B'. These bridges impinge tightly against the side 55 of the inner flange of the rail and force the opposite flange firmly into the clutch of the rod, the lips preventing any lifting of said inner flanges. Back of the bridges are formed 60 large slots D', to give sufficient room for inserting the wedge-key between the upper wall of the slot and the bottom of the groove in the rod should occasion compel the revolving of the collar. Back of the slots the collars are formed of solid metal, as shown.

65 Through the slots in the collars and the groove in the rod pass wedge-keys D D. These keys have split pins p p for holding them when driven in as far as desired, and a series of holes, h h, for said pins. The sloping 70 sides of the keys do not wholly fill the slots of the collars on the inner side. Hence when any slack is observed it may be taken up by driving the keys farther in and fastening them. However, the straight side of the key always 75 bears tightly against the bridge of the collar.

It will be seen that the fastening is secured by driving the wedge-key against the sides of the bridge of the collar and the inner wall of the groove in the switch-rod.

80 A switch-rod and coupler constructed as above described can be made at much less expense than where the key and slot in the rod are placed back of the collars. The latter construction weakens the rod. The former 85 leaves it strong, and it will be preferred by all.

Having fully described my invention, what I claim, and desire to secure by Letters Patent, is—

1. In a switch-rod and coupler, the collar C, 90 having lips c, bridge B', and slot D', substantially as described.

2. The combination of the switch-rod B, grooved to form the solid clutch a and removed rear walls, w, with the collar C, having 95 lips c, bridge B', and slot D', said collar being fastened by a wedge-key passing through it and the groove in the rod, substantially as set forth.

In testimony whereof I affix my signature in 100 presence of two witnesses.

JOHN LOVEJOY.

Witnesses:
